UNITED STATES PATENT OFFICE.

HERBERT W. WOLFF AND ARTHUR LIPSCHUTZ, OF ST. LOUIS, MISSOURI,
ASSIGNORS TO AMERICAN CAR & FOUNDRY COMPANY, OF ST. LOUIS,
MISSOURI, A CORPORATION OF NEW JERSEY.

HOPPER-BOTTOM CAR.

SPECIFICATION forming part of Letters Patent No. 763,706, dated June 28, 1904.

Application filed July 13, 1903. Serial No. 165,279. (No model.)

To all whom it may concern:

Be it known that we, HERBERT W. WOLFF and ARTHUR LIPSCHUTZ, citizens of the United States, residing at St. Louis, Missouri, have 5 invented a certain new and useful Improvement in Hopper-Bottom Cars, of which the following is a full, clear, and exact description, such as will enable others skilled in the art to which it appertains to make and use the 10 same, reference being had to the accompanying drawings, forming part of this specification, in which—

Figure 1 is a side elevational view of one end of a hopper-car constructed according to 15 our invention. Fig. 2 is a longitudinal sectional view of the same. Fig. 3 is a plan view partly in section, and Fig. 4 is an end view partly in section.

This invention relates to new and useful improvements in hopper-bottom cars containing 20 a plurality of hopper-sections which are divided at the center sills, the object being to construct such a car with plate-girder sides and of such general type of construction that 25 the car may be lengthened substantially on the same lines to any convenient length for the purpose of providing for greater or less capacity, as may be desired.

In the drawings illustrating the invention, 30 1 represents plate-girder sides provided with the usual tension and compression members, comprising angles or other rolled shapes secured to the side plates 1 along the top and bottom, in addition to which angles 2 2^a and 35 channels 3 and 3^a are connected with said side plates at such convenient intervals thereupon as may be best adapted to serve the purposes desired for strengthening the several parts and providing a unitary structure of the 40 strength required. The underframing of this car includes continuous bolsters A, extending from side wall to side wall and secured thereto by means of brackets B and fillers C, the said fillers being substantially channel-shaped 45 in cross-section with the middle portion thereof secured to the side walls 1 and the legs connected with the web portions of said bolsters A. End sills D are provided, which may be

of any convenient type best adapted to serve the usual purpose of such end sill; and extending between the end sills D and said bolsters A are short draft-sills E, preferably of pressed steel or commercially-rolled channel-shaped members, as shown. Between the bolsters extends either a single center sill or a 50 plurality of center sill members F F', which members are preferably either commercially-rolled or pressed channel shapes or built-up structures of the same general type as may be best adapted to serve the required purpose. 55 Extending substantially in the same plane with the center sills are transversely-extended girders 4, which in the present instance are represented as comprising commercially-rolled I-beams, which project to a plane above 60 the upper plane of the center sill members, while the lower portion of the cross-girder and said sill members are in substantially the same plane. Extending vertically downwardly 65 from the angle 5 and secured to the plate-girder sides in alignment with said cross-girders 4 are channel-shaped braces 3, which are connected with said cross-girders at the ends of said girders, so as to form supports therefor of such construction that the weight of the 70 structure and load supported by said girders will be distributed to the plate-girder sides. 75

In alignment with the bolsters A are other channel-shaped braces 3^a, connecting the side plates and said bolsters through the filler B 80 of said bolster before referred to. The channels 3 3^a may, if desired, each comprise a single commercially-rolled channel member or may consist of a plurality of angles, according to convenience. By reason of the cross-girders 4, connected with the plate-girder sides and sectional center sills, the same general type of construction may be used in building 85 cars of greater or less lengths and capacity and a greater or less number of hopper-openings may be provided at convenient intervals throughout the length of the car, as may be desired. However, for convenience of illustration but two of such hopper-sections are provided, which hopper-sections are 90 divided by the center sills, so that four hop-

per-openings are shown, said hopper-openings being closed by the same number of doors 6. The general plan of the door-operating mechanism is such that the tendency of the doors 5 at all times is to drop by gravity away from the discharge-openings of the hopper-sections, and the chain, cable, or other lifting means 7 is essential to hold said doors in a closed position, said cable being wound on a drum 10 on the shaft 8 and being connected with the loops 9, attached to said door 6. Connected with the doors 6, substantially centrally thereof, are links 10, which links extend upwardly in an oblique direction and are connected with 15 the side hopper-sheets 11, the connection thereof to said sheet being such that when the link 10 is in a vertical position the door 6 will swing below the hopper-opening, as best shown in Figs. 1 and 2 of the drawings. Connected 20 also with said door 6 and said side hopper-sheets are guide-links 10^a, also obliquely disposed, but more nearly perpendicular than the first-mentioned links 10. The object in so disposing the links 10 10^a is to provide 25 such connection for the door that when the winding cable or chain 7 is released the weight of the load thrown on said doors 6 will cause them to open and by reason of the angular adjustment of the said links will cause a tilting 30 of said doors 6, as best shown in dotted lines in Fig. 2, whereby the load will be more perfectly discharged, after which the doors 6 may be closed by rewinding the cable 7. Connected with the web portion of said trans- 35 verse girder or girders 4 are oppositely-disposed inclined floor-sections 12, which are provided with angles 13, adapted to form frames for said doors 6. Said inclined floor-sections are provided with upwardly-disposed 40 flanges 14 or other convenient means, whereby they are connected, respectively, with said hopper-sheets 11 and with the inner hopper-sheets 11^a, the latter being connected with said center sills, as best shown in the sectional 45 portion of Fig. 4. The said transverse girder 4, with the oppositely-inclined floor-sections 12, being connected with the said plate-girder sides are firmly supported thereby and form the usual transversely-extended ridge com- 50 mon to this class of cars. Suitably supported by the end sills are braces 15, connected, respectively, with said end sills and the end walls G of the car, and from said end walls G to the discharge-opening nearest 55 thereto the end floor-sheets 16 project in an oblique line, said end floor-sheets being flanged upwardly at 16^a and riveted to the side plates 1. Connected with said end braces 15, the channel-braces 18, and the center sill portions 60 F are angles 17, which extend parallel with said inclined end floor portion and serve as supporting means therefor. In addition to said angles 17 said channel-braces 18 extend upwardly from the cover-plate 19 of the bolster and serve as supports for said end floor 65

portions, whereby said inclined end floors are securely supported.

It is obvious that struts of any form may be substituted for the channels 18 and angles 17 shown where desired.

As the hopper-sections are divided centrally by the center sills, a longitudinally-extending deflecting-crown 20 is provided, which extends in substantially the same plane from end to end thereof above said center sills, being 75 provided with downwardly-extended legs 21, which are riveted to the said center sills. This deflecting-crown may be of any convenient shape in cross-section and may consist of a single sheet pressed into the desired 80 shape or of a plurality of sheets riveted together, as may be desired, and it will be noted that the deflecting-crown extends to a plane sufficiently high to extend above the transversely-extended girders before described, the 85 legs 21 of the crown being cut away where said girders extend therethrough, though the deflecting-crown and transverse girders may be in substantially the same plane where desired.

Between the sills door-supporting means are provided, which means may be duplicates of the levers 10 10^a or may comprise single yoke members 10^b, bifurcated at their lower ends, as shown in Fig. 4, said members or yokes 95 10^b being supported by brackets or any other convenient means connected with the center sills, or where the links 10 10^a are duplicated lugs may project inwardly from the center sills and said parts be supported therefrom. 100

With respect to the above construction it will be noticed that the side walls in the form of plate-girders carry the cross-beam 4, which supports a continuous end of the sections of the center sill. The inclined floor-sheets 105 12 form an interrupted cross-ridge, they being riveted to the cross-beam at their upper edge and to the inside and outside hopper-sheets at their ends, thus leaving the space between the inside hopper-sheets free for the 110 door-operating mechanism.

We are aware that minor changes in the construction, arrangement, and combination of the several parts of our device can be made and substituted for those herein shown and 115 described without in the least departing from the nature and principle of the invention.

Having thus described our invention, what we claim as new, and desire to secure by Letters Patent, is—

1. In a hopper-bottom car, plate-girder sides, a continuous cross-girder connected thereto, center sill connected with said cross-girder, and inclined hopper floor-sheets connected with said cross-girder and said plate-girder sides; substantially as described.

2. In a hopper-bottom car, a sectional center sill, plate-girder sides, a cross-girder connected with said sill and said plate-girder sides, continuous bolsters, and draft-sills be-

- tween said bolsters and the end sills of said car; substantially as described.
3. In a hopper-bottom car, plate-girder sides, continuous bolsters connected therewith, draft-sills connected with said bolsters, center sills, a cross-girder connected with said sills and with said plate-girder sides, and braces connected with said sides in alinement with said cross-girders; substantially as described.
4. In a hopper-bottom car, plate-girder sides, continuous bolsters connected therewith, draft-sills connected with said bolsters, sectional center sills, a cross-girder supporting said sills, said girder being connected thereto and with said plate-girder sides, and braces connected with said sides in alinement with said cross-girders and with said bolsters; substantially as described.
5. In a hopper-bottom car, plate-girder sides, an I-beam cross-girder connected therewith, inclined hopper floor-sheets connected respectively with the web portion of said I-beam and with extensions of said plate-girder sides, and center sills supported by said cross-beams; substantially as described.
6. In a hopper-bottom car, plate-girder sides, a continuous I-beam cross-girder connected therewith, inclined hopper floor-sheets connected respectively with the web portion of said I-beam and with extensions of said plate-girder sides, and a center sill supported by said cross-beams; substantially as described.
7. In a hopper-bottom car, plate-girder sides, continuous bolsters, braces connecting said bolsters therewith, sectional center sills, a continuous cross-girder supporting said center sills, and being connected with said plate-girder sides, and inclined hopper-floors connected with said girders and with extensions of said plate-girder sides; substantially as described.
8. In a hopper-bottom car, plate-girder sides, continuous bolsters, sectional center sills, a cross-girder extending to a plane above said center sills, braces connecting said girders with said sides, and inclined hopper floor-sheets connected with the webs of said cross-girders; substantially as described.
9. In a hopper-bottom car, continuous bolsters, plate-girder sides, inclined end hopper-floors connected therewith, supporting-angles substantially coextensive with said floors, braces connected with said supporting-angles, said bolsters and said sides, sectional center sills, a continuous cross-girder, and braces connected with said girders and said sides; substantially as described.
10. In a hopper-car with plate-girder sides, bolsters, a cross-girder fastened to the side girders, a longitudinal beam connected to and supported by the bolsters and cross-girders, an inclined hopper-floor supported by the bolsters and depending from the cross-girders, and hopper sides supported by the side girders, and by the aforesaid longitudinal beams; substantially as described.
11. In a hopper-car, plate-girder sides, a cross-girder extending continuously from side to side, and connected to the side girders, hopper floor portions inclined in opposite directions, and being connected with the said cross-girder, doors extending across the opening between the oppositely-inclined hopper floor portions, and suitable opening and closing apparatus for the doors; substantially as described.
12. In a hopper-bottom car, a hopper-door, supporting-links connected therewith substantially centrally thereof, and a guide-link attached to said door back of its center, whereby said door is inclined by gravity to hang away from the door-opening, and means connected with the forward end of said door adapted to draw the same into position to close said opening; substantially as described.
13. In a hopper-bottom car, plate-girder sides, sectional center sills, inner hopper-sheets connected therewith, a longitudinal deflecting-ridge extending in substantially the same plane from end to end, and a continuous cross-girder supporting said center sills, said girder being connected with said sills and said plate-girder sides, and adapted to support said deflecting-crown; substantially as described.
14. In a hopper-bottom car, a longitudinal deflecting-crown extending past a plurality of hopper-openings, and supporting means therefor comprising plate-girder sides, a continuous cross-girder connected with said sides, and center sills divided longitudinally at said cross-girder and connected therewith; substantially as described.
15. In a hopper-bottom car, a longitudinal deflecting-ridge, center sills and a transverse girder adapted to support said sills near the middle of the car, hopper-doors, means for supporting said door normally away from the hopper discharge-opening and means for closing said doors; substantially as described.
16. In a hopper-bottom car, plate-girder sides, a continuous cross-girder connected thereto, center sills in the plane of said cross-girder, and inclined hopper floor-sheets connected with said cross-girder and said plate-girder sides; substantially as described.
17. In a hopper-bottom car, sectional center sills, plate-girder sides, a cross-girder in the plane of said center sills connected with said sills and said plate-girder sides, continuous bolsters, and draft-sills between said bolsters and the end sills of said car; substantially as described.
18. In a hopper-bottom car, plate-girder sides, continuous bolsters connected therewith, draft-sills connected with said bolsters, sectional center sills, a cross-girder in the plane of said sills connected thereto and with said plate-girder sides, and braces connected with

said sides in alinement with said cross-girder; substantially as described.

19. In a hopper-bottom car, plate-girder sides, continuous bolsters connected therewith, draft-sills connected with said bolsters, sectional center sills, a cross-girder in the plane of said sills connected thereto and with said plate-girder sides, and braces connected with said sides in alinement with said cross-girder and with said bolsters; substantially as described.

20. In a hopper-bottom car, plate-girder sides, an **I**-beam cross-girder connected therewith, inclined hopper floor-sheets connected respectively with the web portion of said **I**-beam and with extensions of said plate-girder sides, and center sills in the plane of said cross-beams; substantially as described.

21. In a hopper-bottom car, plate-girder sides, a continuous **I**-beam cross-girder connected therewith, inclined hopper floor-sheets connected respectively with the web portion of said **I**-beam and with extensions of said plate-girder sides, and sectional center sills in the plane of said cross-beams; substantially as described.

22. In a hopper-bottom car, plate-girder sides, continuous bolsters, braces connecting said bolsters therewith, sectional center sills, a continuous cross-girder in the plane of said sills, connected with said plate-girder sides, and inclined hopper-floors connected with said girder and with extensions of said plate-girder sides; substantially as described.

23. In a hopper-car with plate-girder sides, bolsters, a cross-girder fastened to the side girders, longitudinal beams connected to and supported by the bolsters and cross-girders, an inclined hopper-floor supported by the bolsters and depending from the cross-girder,

and hopper sides supported by the side girders, and by the aforesaid longitudinal beams; substantially as described.

24. In a hopper-bottom car, plate-girder sides, sectional center sills, inner hopper-sheets connected therewith, a longitudinal deflecting-ridge extending in substantially the same plane from end to end, and a continuous cross-girder in the plane of said center sills, said girder being connected with said sills and said plate-girder sides, and adapted to support said deflecting-crown; substantially as described.

25. In a hopper-bottom car, a longitudinal deflecting-ridge, center sills and a transverse girder substantially in the plane of said sills adapted to support said sills near the middle of the car, hopper-doors, means for supporting said door normally away from the hopper discharge-opening and means for closing said doors; substantially as described.

26. In a car, the combination with plate-girder side walls, of a cross-beam carried thereby, center sills which are interrupted in a plane of the cross-beam and connected thereto, center hopper-sheets suspended from the center sill-sections, side hopper-sheets suspended from the plate-girder sides, and inclined plates 12 forming an interrupted cross-ridge, said plates being connected to said hopper-sheets and cross-beam; substantially as described.

In testimony whereof we hereunto affix our signatures, in the presence of two witnesses, this 9th day of July, 1903.

HERBERT W. WOLFF.
ARTHUR LIPSCHUTZ.
